UNITED STATES PATENT OFFICE.

FRED. M. CLOUGH, OF BRYANT, SOUTH DAKOTA.

TYPEWRITER-DESK.

1,392,744.

Specification of Letters Patent.

Patented Oct. 4, 1921.

Application filed October 29, 1919. Serial No. 334,114.

To all whom it may concern:

Be it known that I, FRED. M. CLOUGH, a citizen of the United States, residing at Bryant, in the county of Hamlin and State 5 of South Dakota, have invented certain new and useful Improvements in Typewriter-Desks; and I do hereby declare the following to be a full, clear, and exact description of the invention, such as will enable others 10 skilled in the art to which it appertains to make and use the same.

My invention relates to improvements in office desks having means for supporting a typewriter.

15 An important object of this invention is to provide a desk having a typewriter compartment and novel means for supporting a typewriter whereby the same may be readily brought to an operative position and returned to a compartment for concealing the same from view for the purpose of protection from dust.

20 A further object of this invention is to provide novel means for elevating the typewriter support upon being withdrawn from the compartment.

25 A further object of this invention is to provide a typewriter desk having a turn table mounted thereon and which is adapted 30 for supporting the typewriter in any desired position with relation to the desk.

35 A further object of this invention is to provide a desk having a typewriter support which is neat, of highly simplified construction and simple to operate.

40 A further object of this invention is to provide a typewriter support of the character described which is durable in use and cheap to manufacture.

45 Other objects and advantages of the invention will be apparent during the course of the following description.

In the accompanying drawings, forming a part of this application and in which like 50 numerals are employed to designate like parts throughout the same,

Figure 1 is a perspective of a desk having my improved typewriter support.

55 Fig. 2 is a transverse section through the desk showing the support arranged within a typewriter receiving compartment,

Fig. 3 is a vertical transverse section through the desk, showing the support extended and the table of the same elevated,

55 Fig. 4 is a transverse section through the typewriter receiving compartment.

Fig. 5 is a perspective of a locking device embodied in the invention,

Fig. 6 is a detail sectional view showing the locking means for the inner end of the 60 platform.

Fig. 7 is a plan view of a portion of the table showing the rotary turn table.

In the accompanying drawings forming a part of this application and in which like 65 numerals are employed to designate like parts throughout the same, the numeral 10 generally designates a desk having a flat top 11 and a vertical row of drawers 12 down one side. A central drawer 13 is arranged 70 beneath the top 11 and at one side of a compartment 14. As indicated in Fig. 2, the compartment 14 extends transversely of one side of the desk and is rectangular in shape. A plurality of spaced rollers 15 are mounted 75 in the bottom of the compartment and are adapted to be readily removed for the purpose of replacement. As indicated in Fig. 3, the compartment 14 receives a rectangular platform 16 adapted to slidably engage the 80 anti-friction rollers 15 during its inward and outward movement. A pair of brackets 17 are pivotally connected at their upper ends to the inner walls of the compartment 18 and at their lower ends 19 to the intermediate portion of the platform. The arms or brackets 17 are hinged intermediate their ends as indicated at 20 to permit of the movement of the platform inwardly and outwardly.

90 End walls 22 are horizontally hinged to the platform 16 as indicated at 23 and have their upper ends horizontally hinged to a top wall 24 as indicated at 25. A turn table 26 is rotatably mounted on a vertical shaft 95 27 carried by the top wall 24, and is adapted for supporting a typewriter. A locking arm 28 is carried by the top wall 24 and is provided at its free end portion with a slot 29 adapted to receive a pin 30 carried by one 100 of the end walls 22. When it is desired to lock the top wall 24 in an elevated position, the arm 28 is engaged with the pin 30. When elevated, the top wall 24 may raise the typewriter about seven and one-half 105 inches. A manipulating element 31 is carried by one of the end walls 22 for raising and lowering the top wall 24.

For locking the platform in an extended position I have provided a spring actuated 110 catch 32 having a handle 33. When it is desired to return the platform to a closed

position, the handle of the catch 32 is elevated and thereby released from its locked position. When the platform and the typewriter are pushed within the compartment 5 they are effectively protected from dust and concealed from view.

A door 34 is horizontally hinged as indicated at 35 to the front of the compartment 14 and is provided with a suitable 10 lock 36.

When it is desired to use my improved typewriter support, the door 34 is opened and the platform 16 brought to an extended 15 position. The end walls 22 are subsequently elevated and the typewriter simultaneously elevated.

The arm 29 is now locked with the pin 31 for retaining the top wall 24 elevated.

The turn table 26 permits the typewriter 20 mounted on the same to be adjusted to any desired position.

While I have shown and described the preferred embodiment of my invention, it is understood that such minor changes in 25 arrangement and construction of parts may be made as will remain within the spirit of the invention and the scope of the appended claims.

It will be observed that the brace 17 is 30 extensible to adapt itself to the movement of the drawer platform 16 to which it is connected at a mid length of the latter, and when the catch 32 has been engaged with the socket provided for its reception as the 35 platform reaches the limit of its forward movement or extension, the brace 17 is placed under tension or tensile strain, so that the platform is rigidly supported to resist the vibrations incident to the operation 40 of the typewriting machine. It will also be seen that by disposing the leaves 22 which are horizontally hinged and constitute the connection between the platform and the table 24 in a vertical position when the 45 apparatus is extended for use, any vibrations communicated to the table are conveyed directly to and resisted by the platform braced as above indicated. The catch 29 serves as the means for maintaining the 50 leaves in the indicated upright position.

Having thus described my invention, what I claim is:—

1. A typewriter cabinet having a receiving compartment, a drawer platform movable into and out of the compartment and carrying a vertically movable table connected with the platform by horizontally hinged swinging leaves, means for locking the leaves in an upright position and an extensible brace connecting the platform at midlength with the walls of the compartment for supporting the same when extended.

2. A typewriter cabinet having a receiving compartment, a drawer platform movable into and out of the compartment and carrying a vertically movable table connected with the platform by horizontally hinged swinging leaves, means for locking the leaves in an upright position and an extensible brace connecting the platform at midlength with the walls of the compartment for supporting the same when extended, 65 said platform being provided at its rear or inner edge with a catch for locking the same in its advanced or extended position with the said brace under tensile strain.

3. A typewriter cabinet having a receiving compartment, a drawer platform movable into and out of the compartment and carrying a vertically movable table connected with the platform by horizontally hinged swinging leaves, means for locking the leaves in an upright position and an extensible brace connecting the platform at 80 midlength with the walls of the compartment for supporting the same when extended, said platform being provided at its rear or inner edge with a catch for locking the same in its advanced or extended position with the said brace under tensile strain, 75 and the compartment having its floor provided with anti-friction roller supporting means for said platform.

In testimony whereof I affix my signature 95 in presence of two witnesses.

FRED. M. CLOUGH.

Witnesses:

JAMES ERICKSON,
G. L. DUNN.
